UNITED STATES PATENT OFFICE

96,786

DESIGN FOR A WHEEL

Charles R. Stough, Lansing, Mich., assignor to
Motor Wheel Corporation, Lansing, Mich., a
corporation of Michigan

Application March 18, 1935, Serial No. 55,918

Term of patent 7 years

To all whom it may concern:

Be it known that I, Charles R. Stough, a citizen of the United States, residing in Lansing, in the county of Ingham and State of Michigan, have invented a new, original, and ornamental Design for a Wheel, of which the following is a specification, reference being had to the accompanying drawing, forming a part thereof.

In the drawing:

Figure I is a front view in elevation of a wheel embodying my design;

Figure II is a perspective view of the wheel body shown in Figure I;

Figure III is an enlarged sectional view showing the outer contour of the spoke-like portions in the region of III—III, Figure I; and

Figure IV is a radial sectional view of the

wheel shown in Figure I taken between the spoke-like formations.

The design is essentially disk-like in appearance including a plurality of spaced apart circumferentially elongated openings adjacent its periphery. Spoke-like ribs are formed between these openings. The design is characterized by the size and shape of the spoke-like portions and the manner in which they merge or blend into the peripheral and central portions of the disk. The spoke-like portions have the appearance of having been squeezed on the sides and forced up in the center.

I claim:

The ornamental design for a wheel, as shown and described.

CHARLES R. STOUGH.
